UNITED STATES PATENT OFFICE.

OSCAR H. LAY, OF ANCHORAGE, TERRITORY OF ALASKA.

COMBINATION-TOOL.

1,331,204.

Specification of Letters Patent. Patented Feb. 17, 1920.

Application filed May 26, 1919. Serial No. 299,904.

To all whom it may concern:

Be it known that I, OSCAR H. LAY, a citizen of the United States of America, residing at Anchorage, Territory of Alaska, have 5 invented certain new and useful Improvements in Combination-Tools, of which the following is a specification.

The invention has relation to tools, and aims to provide a tool adapted for a variety 10 of work and embodying a small number of parts as compared with the range of usefulness of the tool, since it embodies elements whereby the tool may be used as a lace leather cutter, edging knife, rivet set, rivet 15 header, screw-driver, and punch.

The drawing illustrates a preferred embodiment of the invention. However, it is to be understood that in adapting the same to meet different conditions, various changes 20 in the form, proportion, and minor details of construction may be resorted to without departing from the nature of the invention as claimed hereinafter.

Referring to the drawing, 25 Figure 1 is a side view of a tool embodying the invention;

Fig. 2 is an edge view thereof;

Fig. 3 is a perspective view of the tool having the members spread to show more 30 clearly the detailed construction; and

Fig. 4 is a perspective view of the lace cutter and binder for holding the side members or blades against the intermediate blade or member.

Corresponding and like parts are referred 35 to in the following description and indicated in the several views of the drawing by like reference characters.

The tool comprises a middle member or 40 blade 1 and side members or blades 2 and 3, the several members being connected by means of a fastening 4 which consists of a bolt passing through openings in one end of the members 2 and 3 and a longitudinal slot

45 5 in the middle member 1. In this manner either one of the members 2 and 3 may be brought into operative position so as not to be interfered with by the other member.

The slot 5 admits of longitudinal adjustment 50 of the member 1 between the members 2 and 3, whereby provision is had for using the member 1 as a stop or guide in connection with either one or both of the members 2 and 3.

55 The member 3 has its free end reduced and stepped, as indicated at 6 to provide

portions of different widths. The reduced and stepped end 6 constitutes a punch for forming openings of different sizes in leather belts and straps. A notch 7 is formed 60 in an edge portion of the member 3 to receive a blade 8 which constitutes a cutter.

The member 2 has an end portion sharpened to produce a knife blade 9 for edging leather or performing any work for which 65 a knife blade is adapted. A notch 10 is formed in an edge portion of the member 2 in position to register with the notch 7 and is likewise designed to receive the 70 blade 8.

The blade 8 has two cuts or notches 11 formed in an edge thereof and extending inward in parallel relation. The cuts or notches 11 are adapted to receive the members 2 and 3 when the blade 8 is fitted in the 75 notches or cuts 7 and 10. The blade 8 is of a length corresponding to the width of the members 2 and 3. Edge portions of the blade 8 project beyond the outer sides of the members 2 and 3, as indicated most clearly 80 in Fig. 2. The blade 8 acts as a binder to hold the members 2 and 3 close against the sides of the intermediate member 1. The end of the blade 8 opposite that provided with the notches or cuts 11 has an intermediate portion beveled, as indicated at 12 to provide a cutting edge which comes between the members 2 and 3 when the blade 8 is in 85 position. The distance between the inner end of the member 1 and the cutting edge 90 of the blade 8 determines the width of the lace when cutting a strap into strips. By adjusting the member 1 between the members 2 and 3 the distance between the blade 8 and the inner end of the member 1 may be 95 varied so that laces or strips of different widths may be cut as required. It will thus be understood that the member 1 acts as a gage or stop for regulating and determining the cut.

Cross-heads 13 are provided at opposite edges of the member 1 at the inner end thereof and the projecting ends are adapted to engage the edges of the members 2 and 3 and prevent movement thereof when the 105 fastening 4 is tightened. It will thus be understood that the fastening 4 is relieved of the strain which ordinarily would be required to hold the blades 2 and 3 in alignment with the member 1. When it is required to throw one of the members 2 or 3 110 out of operative position the fastening 4

is loosened sufficiently to admit of the blade clearing the projecting ends of the cross-heads 13 on the same side therewith, after which the blade is turned so as to project 5 in the direction of the outer end of the member 1. The fastening 4 is now retightened to hold the parts in the adjusted position. The member 1 may be adjusted to regulate 10 the depth of action of the punch 6 or the projecting portion of the knife blade 9, as will be readily understood.

The outer end of the member 1 is formed with a screw-driver point 14 and has an opening 15 and a depression 16 contiguous 15 to the screw-driver point. The opening 15 provides a rivet set, whereas the depression 16 is made rounding so as to act as a swage or upset for the projecting end of the rivet in a manner well understood.

20 The foregoing description and the drawing have reference to what may be considered the preferred or approved form of my invention. It is to be understood that I may make such changes in construction and 25 arrangement and combination of parts, materials, dimensions, &c., as may prove expedient and fall within the scope of the appended claims.

Having thus fully described my invention, what I claim as new and desire to secure by Letters Patent is:—

1. A tool of the character specified, comprising a middle and side members, the middle member being adjustable longitudinally, means connecting the three members,

and a blade engaging the side members and spanning the space formed between them, the distance between said blade and the intermediate member being adjustable.

2. A tool of the character specified, comprising a middle and side members, the middle member being longitudinally adjustable and the side members having edge portions notched, and a blade having an edge portion notched to receive the side members 45 and the latter in turn having the notches thereof receiving the blade.

3. A tool of the character specified, comprising a middle member having a longitudinal slot and spaced lateral projections, 50 side members placed against the middle member and between the lateral projections thereof and having edge portions notched, a fastening connecting the three members and passing through the longitudinal slot 55 of the middle member, and a blade having an edge portion notched to receive the side members and entering the notches in the edge portions thereof, said blade having the edge portion opposite that in which the 60 notches are formed beveled to a cutting edge which extends across the space formed between the said side members.

In testimony whereof I affix my signature in presence of two witnesses.

OSCAR H. LAY.
